UNITED STATES PATENT OFFICE.

LEOPOLD KASPAR, OF OLMUTZ, MAHREN, CZECHOSLOVAKIA, ASSIGNOR TO KASPAR
GETREIDESCHÄLMASCHINE G. M. B. H., OF OFFENBACH-ON-THE-MAIN, GERMANY.

MACHINE FOR HUSKING, PODDING, BRUSHING, OR TREATING GRAIN.

Application filed November 5, 1925, Serial No. 66,986, and in Austria November 20, 1924.

The subject of the present invention is a machine for husking, pulsing, podding, polishing, brushing, or similarly treating grain, pulse, or seeds, in which two or more separate treating chambers are employed in known manner. Whereas, however, in the previously known machines a single charging device is provided which delivers the raw material to the first chamber, whence it is transferred to the second and thence to the third and so on, according to the present invention the charging device is of such construction that two or more chambers may be simultaneously charged from it with fresh raw material. Said charging operations may, however, be arranged to take place successively. An extra valve device is, for that purpose, provided between the charging device and the inlet openings of the individual chambers, the said device being so arranged that individual treating chambers may be temporarily disconnected. This has the advantage that it is possible to work with reduced loading, without the efficiency of the machine being impaired. This is useful during decreased output or when a part of the plant is damaged. Between each pair of treating chambers connected to one charging device there is arranged an intermediate chamber which enables the raw material to be introduced into the chambers from the sides. These intermediate chambers may also be provided with air inlet openings to allow the material to be ventilated, or special chambers arranged between pairs of treating chambers may be provided for said introduction of air.

Each charging device and each valve device is preferably so constructed that the flow of material may be regulated not only in quantity, but also as regards time. The charging and valve devices may be interconnected by their control means and the valve devices may also be connected by the control means with the discharge openings of the chambers in such a manner that when the discharge flap-valves are open, the valve device is closed.

Finally the charging device may even form a part of the valve device, thus simplifying the construction.

The present invention may, however, be

carried out in yet another manner: The known machines with more than two chambers operate as follows: The material to be treated passes through the individual chambers in turn, being discharged successively from one chamber to the next, and is finally withdrawn fully treated from the last chamber. These known machines with more than two chambers possess the advantage over known one-, or two-chamber machines that intermittent operation of the machine is avoided by the obviation of charging and discharging pauses and total unloading of the machine. The invention is based on the fact that by combining machines with one or two drums to form a three- or more chambered machine in which the independent nature of the individual machines is retained, that is, the treated material is discharged from each drum without passing through the other machines, pauses, in the operation, and intermittent working may be obviated. For this reason separate machines are, according to the invention, combined in a unit, forming a machine of three or more chambers, with a common driving shaft, and preferably in addition, with a common valve control shaft. Each of these separate machines, however, works as an independent machine from which the material is discharged separately, intermediate spaces between the said machines providing for the individual ventilation of each machine.

In such an aggregation of individual machines to form a single unit the individual machines may be regulated in such a manner that they may be charged and discharged independently of each other and the material in each drum may be subjected to treatment for any desired period. Preferably the control arrangements are such that the discharging and the immediately subsequent charging of each individual machine are effected while the other machines are in full operation.

The advantages of the introduction of the material into the drums from the side are also retained in such an aggregation of individual machines.

The combination of such machines in a single unit may even be extended to feeding all the machines individually from a single point by means of suitable conveyer

devices, for example, a conveyer screw, intermediate spaces between the individual machines making the introduction of the material from the side possible.

5 Several forms of such a machine are illustrated by way of example in the accompanying drawings in which a preferred embodiment with a charging device for each pair of chambers is shown in Fig. 1 in end elevation, in Fig. 2 in side elevation, in Fig. 10 in partial cross section and in Fig. 4 in longitudinal cross section. Figs. 5 and 6 show a special construction of charging device in section and end elevation. Figs. 7 15 and 8 illustrate in end elevation (partially sectioned), and side elevation, a machine composed of four single-drum machines with common driving and valve-control shafts, each drum being provided with its own feed hopper. Fig. 9 shows in side elevation a machine composed of four single drum machines in which all the drums are fed from a single point, the material being delivered by means of a conveyer screw to 25 the individual drums. Finally Fig. 10 illustrates in side elevation a four chamber machine consisting of two two-chamber machines, a common charging arrangement being provided for each pair of chambers.

30 In the construction illustrated in Figs. 1 to 4, four separate treating chambers are indicated by 1, 2, 3 and 4. The material to be treated passes from the charging devices, that is for example, charging devices 5 and 35 6 provided with valves, 5', 6' or the like, into the chambers 1 and 2 or 3 and 4 through the intermediate charging chambers 7 or 8.

35 The alternate, or simultaneous, charging of chambers 1 and 2 or 3 and 4 by the charging devices 5 and 6 is effected by means of the positive control of regulating flap valves, slide valves, or the like, 10 and 11. The control means of these flaps, slides, or the like, is interconnected with the control means of the discharge flap valves, or the like, 13 to 16 in such a manner that the discharge valves open first, the material to be treated passing out from the chambers in question and out from the machine, and immediately thereafter the chambers are recharged.

40 The control means may, however, be so arranged that, for example, chambers 1 and 4 are filled while chambers 2 and 3 remain empty, the machine then requiring correspondingly less power.

45 In the normal operation of the machine the four chambers discharge in any order, one after the other, and are then immediately recharged, so that the above mentioned but considerably reduced variations in loading last a few seconds only.

50 The introduction of air into the chambers 1 and 4 is effected through openings in the 65 ends of the machine while air is introduced

into the chambers 2 and 3 through the intermediate chamber 9, the air being sucked in through the walls of the intermediate chamber. The air enters the intermediate chamber through air openings in its casing.

55 The material leaving the individual chambers may, for example, be discharged into a screw conveyer path 17 and led by a screw to the common outlet 18.

With normal operation in which the chambers are charged and discharged, not simultaneously, but at different times, the cycle of operations is as follows: On starting up the machine the valve devices (slides 5' and 6' or the like) arranged in the charging devices 5 and 6 are in the open position. The flap valves 10 and 11, or the like are in such a position that the charging openings of one pair of chambers, for example, the chambers 1 and 3 are open, while the charging openings of the other pair of chambers 2 and 4 are closed. The chambers 1 and 3 may therefore be charged with material.

60 The entry of material into chambers 1 and 3 is interrupted by the movement of the valves 5' and 6' into the closed position. At any desired moment the charging openings of the other chambers 2 and 4 may be opened by the reversal of the valves 10 and 11 while the charging openings of the chambers in full operation are at the same time closed, this reversal being effected with the valves 5' and 6' in the closed position. When the valves 5' and 6' are subsequently opened, the empty chambers 2 and 4 are charged with material.

65 The discharge of the individual chambers is effected by the opening of the discharge valves 13, 14, 15, 16, which, however, are preferably not opened simultaneously, but successively at definite intervals, the valve member 5' or 6' of the charging hopper being in the closed position during discharge.

70 A four chamber machine may also be so regulated that each pair of chambers belonging to different charging hoppers, for example, 1, 3 or 2; 4 are charged and discharged simultaneously.

75 The charging and discharging of the chambers during the rotation of the beater wheel 12, or the like, is effected automatically by regulating devices which are driven from the machine shaft 19 and by means of which the valves 5' and 6' are moved alternately into the open and closed positions, the flap valves 10 and 11 reversed and the discharge valves 13, 14, 15, 16 opened and closed.

80 The drive derived from the drum, or machine, shaft 19 may be, for example, arranged similarly to that described in the Austrian patent specification No. 18,513.

85 The driving means or two chambers is diagrammatically illustrated in the drawings: A valve control shaft 20 is driven intermittently by the drum shaft 19 in known manner, through the agency of a cam 21 which inter-

mittently engages with a driver 22 on an intermediate gear shaft driven from the drum shaft 19 through an intermediate gear 23, 24. Cams 25, 26, 27, 28, 29, 30, 31, 32 are mounted on the control shaft 20, cams 25, 26, 27, 28 actuating the discharge valves 13, 14, 15, 16, while cams 29, 30 operate the valves 10, 11, and cams 31, 32 the valves 5' and 6'. The cam 25, for example, operates a pivoted lever 33 which is connected through rods 34, 35 with the discharge valve 13, the discharge valve being opened by a movement of the pivoted lever 33. The cams 26, 27, 28 operate the discharge valves 14, 15, 16 in like manner. Each of the cams 31, 32 cooperates in a similar manner with a pivoted lever which is connected by a rod 36 with the valve 5' or 6' respectively so that each valve may be opened individually by the rotation of the co-operating cam. In the drawing the rod 36 engages with a slotted member 37 connected to the valve 5'. This slotted member enables the point of attachment of the rod 36 to be adjusted, whereby the range of opening of the valve may be altered. The cams 29 and 30 operate rods 38, 39 which actuate crank arms 41 mounted on the spindles 40 of the valves 10, 11.

The cams 29 and 30 are provided with two oppositely situated raised portions 29¹, 29², 30¹, 30². They are slidably mounted on the shaft 20 so that either the portions 29¹, 30¹ or 29², 30² may be brought into engagement. By moving the cam 29 to the right from the position shown in the drawing the timing of the reversal of the valve 10 will be altered. Whereas with normal operation the charging of the chamber preferably follows the discharge immediately and for this purpose the valves 10 and 11 are so regulated that they open later than the discharge valves 13 and 14, it is on the other hand possible by adjustment of the cams 29, 30 to put the raised portions 29¹, 30¹ out of the operation and 29², 30² into operation, whereby the successive operation of the discharging and charging valves of a chamber may be controlled as desired.

The time intervals, within which the movements of the regulating devices follow one another may be arranged to be variable and adjustable by the adjustment of a stop, in the manner disclosed by the Austrian patent specification No. 18,513.

Another construction of the charging device for the material is shown in Figs. 5 and 6, in which the feed device consists of an inlet tube 42 and two valves 43, 44. These valves are provided with openings 45, 45^a, which cooperate with the openings or channels 46, 46^a leading into the chambers in such a manner that when the valve openings are situated over the channel openings, the material may run through the inlet tube 42 into the individual chambers. The valves

43, 44 are operated through valve rods 47, 47^a by the movement of a lever 48 and cam 49. Variation in the quantity charged is effected either by variation of the charging period, the size of opening being kept constant, or by variation of the size of the opening, the charging period being kept constant; the latter may be effected, for example, by adjusting the lever 48 in a slot 50 in the valve rod 47. In the construction shown in the drawing the valve guide 51 is utilized for the introduction of air which enters through openings 52, 52^a and holes 53, 53^a in the side walls of the chambers. With this construction the material may be allowed to extend to the charging point and a special valve in the conveyer device is unnecessary.

In the construction shown in Figs. 7 and 8, 54, 55, 56, 57 are the treating chambers of four individual machines arranged beside one another with intermediate spaces 59, 60, 61. Within an emery jacket 65 in each of these chambers a beater 62 rotates the beaters of all the chambers being rotated by a common driving shaft 58 mounted in bearings 63 and 64. Each chamber is provided with a charging device 66, 67, 68, 69 (hopper or the like) for the material to be treated, by means of which charging device the material is fed into the chambers in a manner in itself known and from which it may be withdrawn by discharge valves 70, 71, 72, 73 through a discharge hopper 74. The control of the charging devices 66, 67, 68, 69 and the discharging valves 70, 71, 72, 73 is effected by a common control shaft 75 which is so regulated that the individual machines may be charged and discharged independently, preferably in such a manner that the discharge of each machine is followed immediately by its charging, the charging and discharging proceeding while the machine is in full operation. 76, 77, 78, 79 are air inlet openings through which air is sucked into the individual chambers. Openings covered by filters 80 allow for the outlet of the air from the individual chambers.

The machine operates in such a manner that the material is fed at desired intervals through the four inlet devices 66, 67, 68, 69 into the respective chambers, is seized by the beater device and is treated by being rubbed on the emery jacket 65 until the discharge valves 70, 71, 72, 73 of the individual machines open, whereupon the treated material leaves the chamber through, for example in the case of the machine 57, the discharge hopper 74.

The charging devices and discharge valves are operated by the common control shaft 75 which may, in known manner, be intermittently thrown out of engagement with the driving shaft whereby the period of

treatment, that is, the period between the operation of the feed devices 66, 67, 68, 69 and that of the discharge valves 70, 71, 72, 73 may be varied at will. Moreover by means of a special device each of the charging devices 66, 67, 68, 69 may be kept continuously closed, a chamber, so disconnected, being then altogether out of operation so that it does not load the machine.

10 The machine illustrated in Fig. 9 differs from the construction according to Figs. 7 and 8 in that a common charging hopper 81 for all the machines takes the place of the separate hoppers. The material is conveyed from this hopper through a screw conveyer 82 to the individual machines and is from time to time permitted to pass into the chambers by means of valve devices 83, 84, 85, 86, as in the construction shown in 15 Figs. 7 and 8. A further difference over the construction according to Figs. 7 and 8 consists in the fact that the intermediate spaces 59, 60, 61 between the peeling chambers are enclosed, a common jacket for all 20 the chambers being utilized for this purpose. This jacket is provided with openings 87 to allow the air into the enclosed space from which it may enter, through openings 88, 89, the treating chambers 55, 56 adjacent to the intermediate space 60, while the outer chambers 54, 57 are provided with air inlet openings 90, 91 at the ends.

The machine shown in Fig. 10 of the drawings consists of two two-chamber machines 92, 93 which are arranged next to each other with an intermediate space 102, the beater devices being driven by a shaft 58 common to the two machines. In this case a common feed device 94 or 95 is provided for each pair of chambers, the material passing from the feed devices through intermediate chambers 96, 97 into the individual peeling chambers. The air enters through openings 98, 99, 100, 101 at the 45 outer ends of the chambers.

I claim:

1. A machine for treating grain comprising a plurality of treating chambers, arranged in pairs, charging conduits extending between the two chambers of each pair, the chambers of each pair having charging openings in fixed connection with the co-operating conduit, valves in said conduits for controlling the communication between 50 the latter and its connected chambers, means for automatically operating said valves at predetermined time intervals, valves for controlling the charging operation both as to time and volume of the charge, and 55 means for automatically operating said last named valves.

2. A machine for treating grain comprising a pair of treating chambers, a charging conduit having fixed simultaneous connection 60 with both of said chambers, a charging

hopper connected with said conduit, a valve for opening and closing the communication between the hopper and the conduit, means for automatically operating said valve to control the amount of the charge, a second valve whereby the communication between said conduit and said chambers is selectively controlled, and means for automatically operating said second valve.

3. A machine for treating grain comprising a series of chambers, charging devices each common to at least two chambers and in permanent connection therewith, valve devices for selectively controlling the communication between the charging devices and said chambers, a discharging valve for each chamber, and automatic means for operating the valve devices and the discharge valves in predetermined sequence at predetermined time intervals.

4. A machine for treating grain, comprising a pair of treating chambers, charging means in fixed simultaneous connection with each of said chambers, means whereby the charging means is automatically thrown into open communication with each of said chambers independently at predetermined time intervals, discharge valves for each of said chambers, and means for automatically maintaining said discharge valves in closed positions during the charging periods and for predetermined time periods thereafter, and for automatically opening the individual discharge valves independently of each other at predetermined time intervals.

5. A machine for treating grain, comprising a pair of treating chambers, charging means in fixed simultaneous connection with each of said chambers, means whereby the charging means is automatically thrown into open communication with each of said chambers independently at predetermined time intervals, means whereby the amount of grain delivered by the charging device to the respective chambers is automatically controlled, discharge valves for each of said chambers, and means for automatically maintaining such discharge valves in closed positions during the charging periods and for predetermined time periods thereafter, and for automatically opening the individual discharge valves independently of each other at predetermined time intervals.

6. A machine for treating grain, comprising a pair of treating chambers, a charging conduit having fixed, simultaneous connection with both of said chambers, a charging hopper connected with said conduit, a valve for opening and closing the communication between the hopper and the conduit, means for automatically operating said valve to control the amount of the charges delivered to said conduit, a second valve whereby the conduit is thrown into open communication with said chambers in sequence, means for

automatically operating said second valve at predetermined time intervals, discharge valves for each of said chambers, and means for automatically maintaining said discharge valves in closed positions during the charging periods and for predetermined time periods thereafter, and for automati-

ically opening the individual discharge valves independently of each other at predetermined time intervals. ¹⁰

In testimony that I claim the foregoing as my invention, I have signed my name this 19th day of October 1925.

LEOPOLD KASPAR.
